Application January 18, 1933, Serial No. 652,272

2 Claims. (Cl. 254—1)

This invention relates to hoists, lifts and jacks, and supporting housings therefor.

The principal object of the invention is to provide in a device of the kind referred to, an elongated, divided housing including complementary base and cover sections, means for releasably securing the sections together, the sections jointly providing at one end a spring cylinder extended axially and having a rod aperture thru its outer 5 end and a scale slot thru one wall, and at the opposite end a worm gear and sprocket socket, there being spaced sprocket chain slots thru the outer end wall of the socket, and a transversely extended worm-way thru the inner walls of the 10 said socket, between the spring cylinder and the worm gear and sprocket socket.

Another object is to provide in a device of the kind referred to, an elongated, two-part housing, divided longitudinally and comprising complementary base and cover sections, means for releasably securing the sections together, there being interiorly provided at one end of the housing an axially extended spring cylinder, and at the opposite end an axially aligned gear and sprocket 20 socket for receiving a worm gear and chain sprocket, there being spaced sprocket chain slots thru the end thereof for engaging a sprocket chain, and a transversely extended wormway cutting thru the inner walls of the said socket 25 for engaging a worm for operating a gear as referred to as mounted in the said socket.

With these and such other objects and advantages in view as may appear in the course of the following specification, attention is now directed 30 to the accompanying drawings wherein is embodied one preferred form of our invention, and wherein

Figure 1 is a side elevation of the hoist as made and assembled in accordance with this invention.

Figure 2 is a section on the line 2—2 of Figure 1.

Figure 3 is a longitudinal section through the housing which contains the main elements of the invention, taken on a plane perpendicular to the section of Figure 2, and being considerably enlarged.

Figure 4 is a side elevation of the assembly shown in Figure 3, the left-hand end of the housing being broken away.

Figure 5 is a detail plan view, partly in section of a medial portion of the housing carrying the slidably mounted worm lock or latch, the ends 55 of the housing being broken away.

Figure 6 is a section on the line 6—6 of Figure 5.

Figure 7 is a detail in perspective of one of the bearing blocks, the same being shown considerably enlarged.

Figure 8 is a section on the line 8—8 of Figure 1.

The invention according to the embodiment represented in the present drawings, comprises an elongated, sectional or divided housing, frame 10 or support 1, including what may be termed a base or main section 2 and a cap or cover section 3, the two sections being complementary one to the other and being secured or fastened together by means of set screws 4 passed into protruding 15 ears or tabs or flanges 5 in a conventional manner. In one end of this housing is formed the spring cylinder 6, the same being closed by end walls 7 and 8, except that the outer end wall 8 is pierced centrally or axially by the pin or rod 20 aperture 9. The wall of this spring cylinder is slotted longitudinally, as shown at 10, the same forming a scale slot, and the adjacent margins of the slot is scale-marked or calibrated from end to end of the slot, as shown at 11. A coil 25 spring 12 is freely seated within the cylinder 6 and a pin or rod 13 is passed down through the end aperture 9 and through the coils of the spring, the inner end of the pin being provided with a head or nut 14 adapted to seat up against a washer 15 which bears upon the inner end of the spring 12. A pointer 16 extends from the washer out through the slot 10 and is thus arranged to move along the slot over the scale marks 30 35 40 45 50 55 60 65 70 75 80 85 90 95 100 105 110 115 120 125 130 135 mounted in transverse alignment in the sections 2 and 3 of the housing 1 which form and enclose the said socket 19. Properly formed and arranged, the sprocket slots 20 are aligned with the 5 sprocket 27 when the said assembly is mounted in place. If desired, a forked guide or spacing lug 29 may be mounted within the socket over the sprocket 27 and secured in place by a screw 30. A sprocket chain 31 is passed through the 10 slots 20 over the sprocket 27, the separator lug 29 serving for facilitating the insertion of the chain and for preventing its becoming locked. The two ends of the chain 31 are provided with work engaging hooks 17a and 17b. A worm 32 15 is extended through the worm-way 21, the ends thereof being preferably journaled in roller bearings 33 mounted in slidable bearing blocks 34 which are turned out as shown at 35 to provide the necessary races for the roller bearing rings. The blocks 34 are formed with beveled cams 36 which are turned inwardly towards the latch slide-way 23 and arranged to stand in alignment therewith. One end of the worm shaft is extended out 20 through one of the blocks 34, as shown at 37 and is squared off at the end 38 for engaging the operating lever 39 for turning the worm. The blocks 34 are confined against outward lateral movement by means of side plates 40 secured in place by set screws 41, one of the plates being 25 apertured as shown at 42 for passing the outer end of the worm shaft. The beveled or flared formation of the races 35 and the bearings 33 seated therein, prevent the inward lateral movement of the blocks 34, so that they are free to 30 move within their slide-ways only towards or away from the socket 19, whereby the worm is carried into mesh with the worm gear 26 or out of mesh therewith. Coil springs 43 are seated within their pockets 24 and are provided at one end 35 with bearing plugs 44 which bear against the adjacent edges of the blocks 34 and normally press those blocks away from the socket 19 and the worm 32 out of mesh with its gear 26. A long, flat worm latch 45 is slidably mounted within the 40 slide-way 23, the same being movable therethrough in a direction lengthwise of itself but transversely of the housing. The latch is held against lateral movement by the walls of its slide-way and additionally by means of a pin 46 seated in the face of the slide-way and extended 45 into an elongated slot 47 formed axially through the body of the latch. The edge of the latch 45 adjacent the bearing blocks 34 is cut out or recessed to form beveled cams 48, complementary 50 to and adapted to coact with the cams 36 of the blocks 34 for pressing the said blocks outwardly against the action of the springs 43, thus causing the worm 32 to mesh with the gear 26, as the latch 45 is pushed in for that purpose. In such 55 operation the beveled surfaces of the respective cams, which are arranged in proper alignment as shown in Figure 3, ride or slide over one another upon the inward movement of the latch, thus forcing the blocks 34 outwardly to the limit of the bevels of the cams, after which the adjacent side margins or edges of the latch cams and bearing block cams pass into engagement with one another, as indicated at 49 in Figure 3, thus 60 locking the elements in that fixed relation until the latch is drawn outward again. The outer or operating end of the latch 45 is provided with a round shank 50 loosely pinned at 51 to the end of the latch. Upon this shank is rotatably mounted 65 a knob 52 which is bored out axially as shown 70 at 53 for receiving the shank. The knob 52 is spring-set to tend to turn in an anti-clockwise direction, by means of a coil spring 54 seated over the shank and braced or secured at its ends to the knob and shank respectively. A sleeve 55 is 75 extended laterally from the housing 1 in alignment with the latch slide-way 23 for freely receiving the inner end of the knob and within which sleeve the knob is adapted to rotate. Within this inner end of the knob is formed a U-shaped groove 56—56a—56b having its legs opening inwardly towards the housing, the inner or bottom side of one leg of this groove being sloped up to form an outwardly disposed shoulder 57. The arrangement of this element is shown in Figure 5. The groove 56 is adapted to engage a spring-set stud 58, seated through a bore 59 formed through the sleeve 55 and a lateral lug 60, formed on the sleeve, the outer end of the bore being enlarged and threaded to receive a screw 61 which carries the coil spring 62, the latter functioning to force the stud outwardly into the groove 56. The arrangement is such that by rotating the knob 52 clockwise within the sleeve 55 against the action of the spring 54, the sloping leg 56b of the groove 56 may be brought into alignment with the stud 58, thus permitting the latch 45 to be thrust inwardly, in which operation the stud passes up over the sloped bottom side of the leg and snaps back of the shoulder 57, thus locking the latch to its inward position. When it is desired to draw the latch out again, the knob is rotated clockwise to bring the uniform leg 56a of the groove 56 into alignment with the stud, which permits the withdrawal of the latch as the stud travels readily through said groove.

In use and operation as for raising a load, the housing 1 is disposed in a pendant manner and the lower hook 17 is placed in engagement with the load or work 18. One of the upper hooks, as 40 17a, is then placed in engagement with a suitable overhead support, represented at 18a in Figure 1. By then rotating the worm 32 in the proper direction, through the use of the lever 39 applied to the squared end 38 of the worm shaft 37, the sprocket chain 31 is fed through the housing 1, passing over the sprocket 27 and through the slots 20, whereby the length of chain 31a is drawn taut and the load is raised. After 45 the housing has traversed the length of chain 31a up to the hook 17a, the length of chain represented at 31b is stretched upward and the hook 17b placed in engagement with the support at a higher point. The hook 17a is then released and 50 by then rotating the worm 32 in a reverse direction, the load 18 is carried to a higher point. This process is repeated until the load is elevated to the point desired. While the use of the device 55 is here illustrated through its application to elevating a load, it is obvious that the tool may be readily adapted for moving a load in a horizontal line, as for stretching line wires or cables or any similar use, through the proper arrangement and engagement of the several work hooks. It is apparent that this tool or hoist possesses 60 very great power inasmuch as the worm is rotated by a lever at great mechanical advantage, and the worm in turn affords further mechanical advantage over the gear and sprocket wheels which pull the sprocket chain and attached loads. Furthermore, the ratio of mechanical movement between the worm and gear is so great that the worm serves to lock the gear against any reverse 65 movement, no matter how great the load that is 70 75

being raised or carried, thus enabling each length of chain 17a or 17b successively to sustain the load while the other length of chain is being attached to a higher or more advanced point.

5 Thus the worm may be rotated and the chain caused to travel in either direction through the housing, with equal facility. This provides a step by step mechanism for raising loads or doing similar work, which is much superior to other conventional devices of the kind.

10 For quick readjustment of the chain and hooks, the worm latch is released in manner already pointed out, thereby releasing the worm from its gear, after which the chain may be rapidly passed through the housing in either direction. The structure is also arranged with the working elements upon which stresses are imposed, all substantially in axial alignment, as shown in the drawings, and with the operating lever disposed laterally at the end of the worm shaft, in the most convenient position.

15 While we have herein shown and described in a general way a certain preferred form or embodiment of our invention and the several elements and structural features thereof, it is understood that we may vary any of the elements by employing equivalents thereof, and may vary or change any of the structural features shown in any matters or details, within the scope of our invention as defined in the appended claims.

20 We claim:

1. In a device of the kind described, an elongated divided housing including a base section and a cover section, the two sections being complementary one to the other, means for releasably securing the two sections together, the two sec-

tions jointly providing at one end a spring cylinder extended longitudinally of the housing, the said cylinder being closed at its outer end except for a rod aperture, the wall of the cylinder being pierced longitudinally by a scale slot, the two sections of housing providing at the opposite end a worm gear and sprocket socket within which a worm gear and chain sprocket may be mounted, there being spaced sprocket chain slots leading thru the outer end wall thereof and thru which a sprocket chain may be extended, and a transversely extended worm-way cutting thru the inner walls of the worm gear and sprocket socket and thru which a worm may be extended in operative engagement with a worm gear as referred to as mounted within the said worm gear and sprocket socket.

2. In a device of the kind described, an elongated two-part housing, the same being divided on longitudinal lines and comprising a base section and a cover section, means for releasably securing the two sections together, there being interiorly provided at one end of the two-part housing a longitudinally extended spring cylinder, and at the opposite end a gear and sprocket socket for receiving a worm gear and chain sprocket, there being spaced sprocket chain slots leading out thru one end wall thereof thru which a sprocket chain may be extended, and a transversely extended worm way cutting thru the inner walls of the gear and sprocket socket and thru which a worm may be extended for operating a gear as referred to as mounted within the said gear and sprocket socket.
